UNITED STATES PATENT OFFICE

2,339,040

HEATING SYSTEM FOR RAILWAY CARS

Kurt E. Zeidler, Chicago, Ill., assignor to Standard Railway Devices Company, Chicago, Ill., a corporation of Delaware

Application April 3, 1942, Serial No. 437,505

4 Claims. (Cl. 237—31)

The invention relates to so-called railway refrigerator cars and particularly to means for heating such cars. The railroads and car operating companies have in service a large number of such so-called refrigerator cars, the essential feature of which is an insulated body and which usually includes means to refrigerate the interior of the car and means to supply air from the outside to the interior of the car.

The conventional refrigerator car, which is commonly called an end bunker car, has an ice bunker at each end of the car and the lading compartment between the ice bunkers. When ice is placed in the bunkers, the cold air circulates from the ice bunkers under the foraminous rack which supports the lading and then filters upwardly through the lading compartment, thereby refrigerating the lading. In cold weather, a heater is placed in one or both bunkers and the air warmed by the heater circulates over the top of the lading and filters downwardly therethrough to heat such lading.

An overhead bunker type of refrigerator car has been developed by my assignee, a typical design of which is shown in Bonsall Patent 2,136,999 of November 15, 1938. In this car the end bunkers have been eliminated and consequently the conventional location for the heaters has also been eliminated. There has been developed an underslung heater suspended below the floor of the car and arranged to heat the car by means of fluid circulating in pipes under the floor rack of the car, the fluid being heated as it flows through a coil disposed within the underslung heater. Such a device has given satisfactory service but is objectionable in many cases because of its weight and cost and furthermore because it is a permanent installation and must be carried with the car during warm as well as cold weather.

An object of my invention is to provide a heating system the major parts of which are easily removable and replaceable so that the system may be installed in cars at the approach of cold weather and removed at the end of the cold season, as will be hereinafter described in detail. The removal of the heating system is a relatively simple operation and the car with the heating system removed refrigerates with unimpaired efficiency.

Another object is to provide a heating system which is equally well adaptable to both the above described conventional end bunker car and to the recently developed overhead bunker car.

Another object is to provide a heating system

which utilizes the conventional portable charcoal heater. Such heaters, which are made by several heater manufacturers, are reasonably well standardized as to dimensions, operation and fuel capacity and the railroads own many thousands of such heaters which they have distributed along their lines at points where refrigerator car trains are serviced. At these points, the heaters are either removed, installed, lighted or extinguished as conditions dictate. While I have shown my invention adapted to use a conventional portable charcoal heater, it is to be understood that it is not limited to the use of such a heater but may be easily adapted to use practically any type of heater desired.

Another object of the invention is to provide a system of hot air distributing ducts under the floor rack to conduct air from the heater to all parts of the car.

Another object, particularly adaptable to the above mentioned overhead bunker cars which embody side wall flues, is to provide for a flow of warm air upwardly through one or more of such side wall flues so that the warm air descends through the lading from the upper part of the car and the ascending warm air further insulates the walls.

Other objects and advantages of my invention will be apparent from the following detailed description by referring to the accompanying drawings.

In the drawings:

Fig. 1 is a transverse section of an overhead bunker refrigerator car embodying my invention.

Fig. 2 is a longitudinal section on line 2—2 of Fig. 1.

Fig. 3 is a plane section on line 3—3 of Fig. 1.

Fig. 4 is a view similar to the lower part of Fig. 1 showing a modified form of my invention.

Fig. 5 is a plan section on line 5—5 of Fig. 4.

Fig. 6 is a section on line 6—6 of Fig. 4.

The general parts of the refrigerator car shown are insulated roof A; side walls B; end wall C; floor D; refrigerant containers E; hatches F for loading refrigerant into the containers E; side wall flues G; foraminous floor rack H and space J between the rack H and the floor D. The spaced apart refrigerant containers E are positioned immediately below the roof A and respectively adjacent the side walls B. A drip pan K is provided below each container E and a partition L is disposed in an upstanding position at the edge of each drip pan K, the drip pans K and the partitions L cooperating with the roof A and the upper parts of the side walls B to form

55

enclosures M around the containers E. Air inlet openings N to the enclosures M are provided by spacing the partitions L from the roof A and air discharge openings P lead from the enclosures M to the flues G at a lower elevation than the air inlet openings N. The refrigerant containers E are preferably spaced apart longitudinally of the car to provide air passages between the ends of the containers. The partitions L are spaced apart to form a duct Q which communicates between the lading compartment R and openings N.

Air circulation during refrigeration is as follows: Air in the lading compartment R is warmed by contact with the lading and rises through the duct Q to enter the enclosing structures M through the air inlet openings N. The air is then cooled by contact with the cold refrigerant containers E and falls by reason of its lower temperature and therefore greater density through the discharge openings P and flues G to the space J whence it rises through the rack H to the lading compartment R. The above described cycle is thereafter continuously repeated.

In the modification of my invention shown in Figures 1 to 3, a downwardly diverging opening 2 is provided in the floor D and surrounded by a frame 3. An insulated receptacle which in the form shown is a box 5 having an open top is removably supported below the floor D with the upper edges of its outer walls 4 fitting within the opening 2 and engaging the frame 3. The box 5 is preferably supported by straps 6 removably secured to the cross members 9 of the under-frame. An insulated door 9 for closing the opening 2 when the box 5 is removed is hinged (11) below the floor D and mounted upon a horizontally slotted hinge butt 12. The door 9 may be confined between the box 5 and certain of the straps 6 when not in use, as shown in Figure 2.

The floor rack H is comprised of longitudinally extending slats 13 supported by transversely extending stringers 16. A baffle 18, preferably formed of wood or other insulating material and faced with metal 19 on its lower side, extends between certain stringers 21 which are disposed above the floor opening 2, thereby forming a passage 22 between the baffle 18 and the floor D, which passage 22 extends substantially between opposite side walls B of the car. When the car is used as a refrigerator, the cold air descending through the side flues G may flow over the top of the baffle 18 and thence upwardly through the rack H into contact with the lading. The box 5 is provided with insulated false walls 24 aligned with and engaging the floor rack stringers 21. The false walls 24 are spaced from the bottom 25 of the box 5 and are also spaced from adjacent outer walls 4 of the box to form air flues 27. A door 28 is preferably provided in the box 5 in the front side or side parallel with a car side wall B.

The type of heater disclosed is a well known type of cylindrical shape with the outer shell having horizontal corrugations. The heater 32 is positioned within the box 5 and confined in a compartment formed by the false walls 24, the rear wall 23 and the door 28 and held preferably in spaced relation to such walls and door by spacers 35. The heater can be lighted and extinguished by opening the door 28 and may be easily removed through the doorway for purposes of refueling.

The heater 32 warms the air adjacent thereto and causes such air to rise; this rising warm air

induces a downward flow of air through the flues 27 between the walls 4 and false walls 24 of the box 5, which latter air is drawn from the space J under the floor rack H. Notches 36 are preferably provided in the lower edges of the floor rack stringers 16 to facilitate flow of air toward the box 5. The air warmed by the heater 32 flows upwardly by natural convection and is directed by the baffle 18 in opposite directions through the passage 22 toward the side walls B of the car. The major part of such warmed air preferably flows upwardly through the side wall flues G to the refrigerant enclosures M and then downwardly through the duct Q to the lading compartment R. The air then filters downwardly through the lading compartment R and gives up heat to the lading. Such a cycle of air circulation is maintained by natural convection inasmuch as the air injected into the side wall flues G is warmer than the air in the lading compartment R. The warm air in the side wall flues G serves the further function of increasing the insulation of the walls B and preventing infiltration of cold air therethrough.

In the modification shown in Figures 4 and 5, the box 5 and the heater 32 are substantially the same as shown in Figures 1 to 3. The floor rack H is comprised of the usual longitudinal slats 40 and transverse stringers 41 preferably hinged (42) to the car side walls B in the conventional manner. The left part of the rack as shown in Figure 4 includes a longitudinally extending duct 43 adjacent the center of the car which duct is formed of light gauge metallic sheet reinforced by straps 44 and rigidly attached to the floor rack H. The baffle 46 extends between the stringers 47 which are disposed above the floor opening 2 to form a passage 49 between the baffle 46 and the floor D for the purpose of conducting warm air from the box 5 to the longitudinal duct 43.

The duct 43 is provided with a plurality of openings 58 distributed from end to end of the car, preferably larger openings being provided remote from the heater 32 to equalize distribution of air into the space J below the floor rack H. The warm air flowing from the duct 43 through the openings 58 into the space J filters upwardly through the lading compartment R and warms the lading. After having been cooled by contact with the lading, the air then settles either through the lading compartment R or through the side wall flues G to the space J under the floor rack H and then is drawn downwardly through the flues 27 in the box 5 to displace the air warmed by the heater 32 and directed into the longitudinally extending duct 43.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A heating structure for use in a refrigerator car having a lading compartment, a foraminous rack spaced from the floor thereof, to provide a space therebetween, flues associated with opposite side walls of said car, communicating at their lower ends with said space and at their upper ends with said lading compartment; said heating structure comprising a heater suspended below said floor, a duct extending transversely of said car below said rack and communicating with said flues, whereby air heated by said heater

is delivered to said duct and thereby to the bottom of said flues on opposite sides of said lading compartment and from the upper end of said flues to the upper part of said lading compartment and downwardly therethrough to said space and finally to said heater.

2. A heating structure for use in a refrigerator car having a lading compartment, a foraminous rack spaced from the floor thereof to provide a space therebetween, flues associated with opposite side walls of said car communicating at their lower ends with said space and at their upper ends with said lading compartment, closed chambers adjacent said roof, each having an air outlet communicating with the adjacent side wall flue and an air inlet communicating with the lading compartment at a higher elevation than said outlet for convective air circulation therethrough, said air inlet being adjacent the longitudinal center of the car; said heating structure comprising a heater suspended below the floor, a duct extending transversely of said car below

said rack and communicating with said flues, whereby air heated by said heater is delivered to said duct and thereby to the bottom of said flues on opposite sides of said lading compartment and from the upper end of said flues to the upper part of said lading compartment and therethrough to said space and finally to said heater.

3. A structure as set forth in claim 1 including a manifold adjacent each side wall of the car communicating with said duct and a plurality of flues in said side wall, whereby the heated air may be distributed by said flues throughout the length of the lading compartment.

4. A structure as set forth in claim 2 including a manifold adjacent each side wall of the car communicating with said duct and a plurality of flues in said side wall, whereby the heated air may be distributed by said flues and chambers to the lading compartment adjacent the longitudinal center thereof throughout the length of said lading compartment.

KURT E. ZEIDLER.
